SHARPENING ROD

Robert N. Farquharson, Bradford, Pa., assignor to W. R. Case & Sons Cutlery Co., Bradford, Pa.

Filed Mar. 15, 1971, Ser. No. 124,653

Term of patent 14 years

Int. Cl. D8—05

U.S. Cl. D8—93

FIG. 1.

FIG. 2.

FIG. 3.

FIG. 4.

FIG. 1 is a front elevational view of a sharpening rod, showing my new design;

FIG. 2 is a side elevational view thereof;

FIG. 3 is an end view taken from the upper end of the device as shown in FIGS. 1 and 2; and

FIG. 4 is an end view taken from the lower end of the device as viewed in FIGS. 1 and 2.

The sides opposite to the sides shown in FIGS. 1 and 2, respectively, are identical thereto.

I claim:

The ornamental design for a sharpening rod, substantially as shown and described.
